CALENDARS

Maier Berlin, Milan, Italy

Application September 27, 1954, Serial No. 458,591

Claims priority, application Italy March 16, 1954

4 Claims. (Cl. 40—112)

2

invention, combined with writing means, to note down memoranda or the like.

In same drawings:

Fig. 1 is a perspective view of the calendar according to the invention.

Fig. 2 is a cross-section thereof.

Fig. 3 is a longitudinal section.

Fig. 4 is a plane of calendar with cover removed, and

Fig. 5 is a detail of Fig. 4.

10 Referring now to aforesaid figures, the calendar as shown consists of a base 10, which in the present case is box-like shaped, and shows a front side 12 open and conveniently shaped, to allow the upper sheet of a pile, fitted in the box-like base 10, to be withdrawn therefrom, after having recorded notes or memoranda thereon.

15 The calendar is fitted within a container 14, which on its turn is fitted in the base 10. In the case in question (box-like base 10) the connection between same base and the container 14 is set by means of hinges 15, which allow 20 a relative motion of base in respect of container in order to ensure an easy access to either of said components.

25 A plate 16 is fitted in the inside of container 14, and is secured thereto by means of the screws 18, being the upper face of said plate very near to inside face of container.

30 A ring 22 is rotatably fitted in a circular abutment 20 with which the upper face of plate 16 is provided. The first thirty one natural numbers (i. e. the max. number of days in a month) are marked in sequence on the fore face of said ring 22.

35 The teeth or tooth gears 24 and 26 are cut on both inner and outer peripheral edges of ring 22. The names of the week days—i. e. Monday, Tuesday, etc.—are stamped on the upper face of a disk 30, secured to a pinion 28, which is engaged with the teeth 26. The transmission ratio of teeth 26 to pinion 28 is set in such a manner that, when the ring 22 is advanced by a step (i. e. is brought from a number to the subsequent one), the disk 30 is also advanced by a step, i. e. it is brought 40 from a day to the subsequent one. Thus, when the teeth 26 are sixty two, as shown by way of example in the accompanying drawing, a pinion with fourteen teeth must be used, whereby the indications of ring 22 can be synchronized with those of disk 30.

45 To the purpose which will be hereinafter stated, the pinion 28, together with its disk 30, is supported by a journal 32 fitted on the slide 34, running on the guides 36, radially formed on the circular stop 20. A knob 35, fitted on one end of said slide 34, projects out of casing 14.

50 The slide 34 is acted upon by the blade spring 38, which tends to keep the pinion 28 continuously engaged with the crown gear 26. By depressing the knob 35, against the action of the spring 38, the pinion 28 is brought out of mesh from the crown gear 26, whereby 55 the ring 22 can be moved independently from the disk 30. All this in order to have—above all at the beginning of each month—the numeration of day months synchronized with the indication of week days.

56 The names of year months are stamped on the face of 60 a further disk 40, fitted diametrically opposite to disk 30. Said disk is secured to a twelve (or a multiple of twelve) teeth pinion, arranged in such a manner as to have their teeth conveniently spaced from those of crown gear 26. However and as already stated, a longer auxiliary tooth 65 44 is added and suitably fitted to said crown gear, in order that it is allowed to engage the teeth of pinion 42, thus causing a corresponding angular motion of disk 40.

66 The pinion 42 is keyed onto a journal 46, provided 70 on one end with a knob 48, that serves for the quick driving of disk 40. The projections 54 and 56, formed on suitable positions of inside face of casing 14, are respectively engaged with the notches 50 and 52, cut on

This invention relates to a calendar, and particularly to a desk calendar, actuated by only one control knob.

Many types of calendars are already known. Such calendars usually consist of rollers, disks, annular bands or the like, whereon the days of the month, the days of the week and the months of the year are marked in their proper sequence.

The single components of such series are combined with respective control devices, as knobs or the like, part of which must be actuated by the user each day, in order to have the various indications correctly up-to-dated one another.

As it will be readily appreciated, the actual usefulness of a calendar is greatly restricted by such annoying operations.

The above stated, and further drawbacks are positively obviated by this invention, which allows to obtain a calendar of the aforespecified type wherein all elements are actuated by only one control knob, being thereby possible to have same calendar actuated automatically, e. g. by a clock.

The calendar according to the inventive idea is characterized in that it comprises at least three components, whereon the days of the month, the days of the week and the months of the year are marked in their correct sequences, being same components connected one another by trains of gears. One of such trains of gears is directly actuated by a control knob which, when turned, causes the elements whereon the week days and month days are marked, to be advanced by one step, being disengaging devices—which allows to obtain the required concordance of month days in respect of week days—interposed in the connection between said elements.

In an advantageous embodiment form of calendar according to the invention, the month days are marked on one face of an annular member, while the week days are marked on a disk, secured to a pinion which can be engaged with the teeth cut on the outer periphery of aforesaid annular member. Further components of the device are: a support for said pinion; spring means to move said support, in order to disengage same pinion from the annular member teeth, a second pinion secured to a disk, whereon the month days are marked; an auxiliary tooth added to normal teeth of annular member and designed to advance latter pinion step-by-step after each complete revolution of said annular member, and a control knob, connected to said annular member in such a manner that, when actuated, both the first stated pinion and the annular member are advanced by a step, while the second pinion will be advanced by a step after each complete revolution of the annular member.

The invention will be hereinafter disclosed in the following description of an advantageous embodiment form thereof, taken with the accompanying drawings, being same description and drawings given only as a not restrictive example.

The embodiment form as shown in the accompanying drawings consists in a desk calendar according to the

the faces of the disk 40 and 30. The notches 52 of disk 30 are longer than the notches 50, in order to allow same disk to be moved when the knob 35 is actuated.

The notches 50—52 and the projections 54—56 engaged therewith have been provided in order to set the exact angular positions of said disks 30 and 40 depending on the controls performed thereto. To such a purpose, said disks are provided with spring means (as f. i. the little springs threaded on the journals 34—36) to resiliently force the disks against the projections 54—56.

The pinion 58, that meshes with the crown gear 20 cut on the outside edge of disk 22, is secured to one end of a control knob 60, which opposite end comes out of casing 14, and is easily accessible, in order to allow the ring 22 and the disks 30 and 40 to be synchronously moved by only one control action.

The numbers and signs stamped on the faces of ring 22 and of disks 30 and 40, can be read from the outside of casing 14 through the window 62 (pertinent to ring 22), 64 (disk 30) and 66 (disk 40).

As shown by Fig. 1, said windows are symmetrically arranged on the vertexes of an isosceles triangle, whereby the last two of same windows are located on the same line.

As it is to be understood, by acting on the knob 60 the ring 22 is turned, whereby a given angular motion of disks 30 and 40 takes place. However, the disk 40 is advanced by a step ($\frac{1}{12}$ of a turn) only after each whole revolution of ring 22.

Since in the aforescribed and illustrated embodiment form, the ring 22 and the disks 30 and 40 can be actuated by means of only one control knob, said embodiment form may be advantageously combined with clock-work mechanisms, i. e. to have clocks or the like with built-in calendars according to the inventions.

Further auxiliary devices, as f. i. signal devices or the like, could also be embodied in the previously described and illustrated embodiment form of calendar according to the invention.

In the case as illustrated, the bevel gear 68, keyed on the journal 32 of pinion 28, drives—through the pinion 70, a first pair of gears 72 and a second pair of gears 74—a drum 76 fitted in the inside of casing 14 and readily accessible from the outside through a window 78. Thus, when the knob 60 is actuated, the drum 66 is also correspondingly driven.

Pictures or signs or the like (as f. i. the symbols representing the months or seasons) could be printed on the outside surface of said drum, and in such a case the drive of drum 66 could also be derived in an equivalent manner from the journal 46.

Many variants could be made to the previously described embodiment form, without exceeding the limits of the claimed patent rights.

Thus, f. i., a drum, or also an annular, flexible member could be substituted for the ring 22. Moreover, the control knob 60 could be fitted on the journal 32 of pinion 28.

It is to be understood that the invention is not limited to the exact details of construction shown and described, as variations and modifications and changes may be made therein as fall within the scope of the claims hereunto.

What I claim is:

1. In a calendar device, in combination, a support; annular date indicia means turnably mounted on said support for movement relative thereto in such a manner as cyclically to indicate thirty-one days of the month; moving means connected to said date indicia means for moving the same through complete cycles of indications; day indicia means turnably mounted on said support for movement relative thereto in such a manner as cyclically to indicate the seven days of the week; coupling means connected to said date indicia means and

said day indicia means and movable between a coupling position wherein said date indicia means and said day indicia means are coupled to each other in such a manner that said day indicia means is moved through one-seventh of its cycle during movement of said date indicia means through one-thirty-first of its cycle and an inoperative position wherein said date indicia means and said day indicia means are disconnected from each other, said coupling means including gear means formed along the inner annular edge of said annular date indicia means and a pinion carried by said day indicia means for rotation therewith, said pinion being capable of meshing with said gear means of said date indicia means, said coupling means further including mounting means for mounting said day indicia means for sliding movement toward and away from said inner annular edge of said date indicia means between two positions in which said pinion on said day indicia means and said gear means on said date indicia means are in and out of engagement with each other, respectively, said last-mentioned two positions constituting, respectively, said coupling and inoperative positions of said coupling means; biasing means for constantly biasing said coupling means into its coupling position; and operating means for moving said coupling means to its inoperative position against the action of said biasing means, whereby said moving means may, while said operating means is not actuated, move said date indicia means through the major portion of its cycle while simultaneously moving said day indicia means and whereby said moving means may, while said operating means is actuated, move said date indicia means through the end portion of its cycle without simultaneously moving said day indicia means through any portion of its cycle.

2. The combination defined in claim 1 wherein said date indicia means is formed along its outer annular edge with additional gear means, and wherein said moving means includes a pinion member in meshing relationship with said additional gear means of said date indicia means.

3. In a calendar device, in combination, a support; annular date indicia means turnably mounted on said support for movement relative thereto in such a manner as cyclically to indicate thirty-one days of the month; moving means connected to said date indicia means for moving the same through complete cycles of indications; day indicia means turnably mounted on said support for movement relative thereto in such a manner as cyclically to indicate the seven days of the week; first coupling means connected to said date indicia means and said day indicia means and movable between a coupling position wherein said date indicia means and said day indicia means are coupled to each other in such a manner that said day indicia means is moved through one-seventh of its cycle during movement of said date indicia means through one-thirty-first of its cycle and an inoperative position wherein said date indicia means and said day indicia means are disconnected from each other, said first coupling means including first gear means formed along the inner annular edge of said annular date indicia means and a first pinion carried by said day indicia means for rotation therewith, said first pinion being capable of meshing with said first gear means of said date indicia means, said first coupling means further including mounting means for mounting said day indicia means for sliding movement toward and away from said inner annular edge of said date indicia means between two positions in which said first pinion on said day indicia means and said gear means on said date indicia means are in and out of engagement with each other, respectively, said last-mentioned two positions constituting, respectively, said coupling and inoperative positions of said coupling means;

operating means for moving said first coupling means between its coupling and inoperative positions, whereby said moving means may, while said first coupling means is in its coupling position, move said date indicia means

through the major portion of its cycle while simultaneously moving said day indicia means and whereby said moving means may, while said first coupling means is in its inoperative position, move said date indicia means through the end portion of its cycle without simultaneously moving said day indicia means through any portion of its cycle; month indicia means turnably mounted on said support for movement relative thereto in such a manner as cyclically to indicate the twelve months of the year; and second coupling means connected to said date indicia means and said month indicia means for coupling the same to each other in such a manner that said month indicia means is moved through one-twelfth of its cycle upon completion of movement of said date indicia means through a complete cycle thereof, said second coupling means including a twelve-teeth second pinion carried by said month indicia means for rotation therewith and a single tooth element arranged along said inner annular edge of said annular date indicia means and capable of meshing with said second pinion.

4. The combination defined in claim 3 wherein said tooth element of said second gear means projects inwardly toward the center of said annular date indicia means further than the teeth of said first gear means.
